(57) CLAIM

The ornamental design for a beverage maker, as shown and described.

DESCRIPTION

FIG. 1 is a perspective view as seen from the top, front and right side of a beverage maker showing the new design;

FIG. 2 is a front view thereof;

FIG. 3 is a right side view thereof;

FIG. 4 is a rear view thereof;

FIG. 5 is a top view thereof; and,

FIG. 6 is a left side view thereof.

The bottom view is omitted as it devoid of claimed ornamentation. The broken lines in the drawings are included for illustrative purposes only and form no part of the claimed design.

1 Claim, 6 Drawing Sheets
